UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,274,092.

Specification of Letters Patent. Patented July 30, 1918.

Application filed July 20, 1915. Serial No. 40,883.

To all whom it may concern:

Be it known that I, DUDLEY S. SEYMOUR, a citizen of the United States, residing at Oak Park, in the county of Cook, State of Illinois, have invented certain new and useful Improvements in Presser-Feet for Sewing-Machines, of which the following is a description, reference being had to the accompanying drawing and to the figures of reference marked thereon.

The invention relates to new and useful improvements in a presser foot for sewing machines, and more particularly to a presser foot adapted to be used in connection with a machine for trimming the edges of fabric sections in advance of the stitching mechanism.

An object of the invention is to provide a presser foot of the above character with means for deflecting the trimmed off strip, which deflecting means is so connected with the presser foot that it may be swung laterally and upwardly from normal position for the purpose of giving access to the needles for threading.

A further object of the invention is to provide a presser foot of the above character having means to support the stationary member of a trimming mechanism with a strip deflector which extends across the foot in advance of the trimmer and which is pivotally connected to the foot so as to swing in a plane inclined to a vertical plane containing the line of feed, whereby the deflecting means is raised free of the stationary trimmer and its clamping parts as it is turned to inoperative position.

A still further object of the invention is to provide a presser foot of the above character with a removable plate having a plurality of needle slots and stitch fingers extending into the same over which the threads are laid during the formation of the stitches.

These and other objects will in part be obvious and will in part be hereinafter more fully disclosed.

In the drawings,—

Figure 1 is a side view of a presser foot having my improvements applied thereto; Fig. 2 is a front view of the same, the arrow indicating the direction of the swinging movement of the strip deflector when turned to inoperative position;

Fig. 3 is a plan view of the presser foot; Fig. 4 is a view partly in transverse sec-

tion, showing the strip deflector turned to inoperative position and in front elevation;

Fig. 5 is a bottom plan view of the presser foot.

Fig. 6 is a side view of the presser foot, showing a slightly modified form of the supporting means for the deflector; and

Fig. 7 is a sectional view on the line x—x of Fig. 6.

My improved presser foot consists of a supporting shank 1, having a foot 2. The shank is provided with a socket 3, which receives the lower end of the presser bar. Said shank is also provided with a rearwardly extending arm 4, which is forked to slidably engage a bar which prevents the foot from turning on the presser bar. The foot 2 consists of a main section 5 and an auxiliary section 6. The auxiliary section 6 is supported, so that it may yield vertically and move to a position slightly below the main section, as shown in Fig. 2. The foot portion 2 is also provided with a removable plate 7 (see Fig. 5) which is in effect a part of the main section 5. This plate is secured to the shank of the presser foot by a screw 8, which extends down through the socket 3 for the presser bar and is threaded into the plate, see Fig. 4.

The plate 7 is provided with two needle openings 9 and 10. The needle openings have stitch fingers 11 and 12, respectively. These needle openings are arranged one substantially in rear of the other. There is, of course, a stitch forming mechanism including a pair of needles operating through each needle opening and cross threads are laid across these stitch fingers.

The presser foot is provided with a guiding slot 13 which is located directly in advance of the needle openings and this slot is for the purpose of directing the upturned edges of fabric sections which are to be trimmed and stitched. After the sections are trimmed the edges are abutted and a flat seam is made. The main section 5 of the presser foot has a recess in which is located the stationary blade 14 of a trimming mechanism. The blade is held on its seat by a clamping plate 15 and a clamping screw 16.

A strip deflector 17 is supported by the shank of the presser foot and extends across this slot 13 directly in rear of the active portion of the trimming edge of the trimming

blade 14 and in advance of the needle openings. This strip deflector is for the purpose of deflecting the trimmed off strip away from the stitching mechanism. The strip deflector is in the form of a plate bent to a suitable shape for deflecting the strip and said plate is clamped to an arm 18 by means of screws 19-19. The arm 18 is formed with a perforated lug 20, see Fig. 4, which 10 extends between projecting lugs 21 and 22 on the shank of the presser foot 1. A pivot pin 23 passes through these lugs and serves as a pivot pin for the arm 18. This pivot pin, as clearly shown in Fig. 4, is inclined 15 to the vertical. The strip deflector 17 is capable of being swung about this pivot pin from the normal position across the guiding slot 13, as shown in Fig. 3, to an inoperative position, as shown in Fig. 4. This gives access 20 to the needles for threading. The strip deflector when in normal position has its lower edge close to the upper face of the presser foot, so as to deflect very narrow strips cut from the edges of the fabric sections by the trimmer. The clamping plate 25 and the screw which holds the same therefore extend above the lower edge of the strip deflector when in normal position. The inclining of the pivot pin, however, causes the strip deflector to swing upwardly as well as laterally when it is moved to inoperative 30 position and this causes the lower edge of the strip deflector to clear the clamping plate for the stationary trimming blade.

In Fig. 6 of the drawings, I have shown a slightly modified form of the invention. The presser foot and the parts supported thereby are precisely the same in construction as above described, except as to the 40 means for supporting the arm 18 which carries the strip deflector. In this form of the invention, the arm 18 has a rearwardly projecting lug 24 which swings on the pivot pin 25. The pivot pin 25 is arranged vertically. The lug 24 is narrower than the distance 45 between the supporting lugs 21 and 22 on the presser foot shank and a spring 26 encircles this pivot pin. Said spring rests against the upper face of the lug 24 and 50 against the lower face of the upper lug 21. The lower face of the lug 24 is beveled, as at 27, while the upper face of the lug 22 is beveled as at 28. As a consequence, when the arm 18 is swung outwardly, these beveled 55 faces cause the arm to be raised and the resulting movement of the arm is in a plane parallel to the contacting beveled faces and this plane is similarly located to the plane of movement of the deflector pivoted as described in Figs. 1 to 5.

The arm 18 is held in normal position with the deflector across the guiding slot, by the leaf spring 28, which is secured to the arm 18 by screws 29 and extends rearwardly 60 and bears against the lugs 21 and 22. These

lugs are formed with a square shoulder 30, and said spring bears against one face of the shoulder to hold the arm in the position above stated. When the arm is swung outward to move the deflector to inoperative 70 position, as shown in Fig. 1, then said leaf spring bears against the other flat face of the shoulder 30. This retains the deflector in said position.

It is obvious that minor changes in the 75 details of construction and arrangement of parts may be made without departing from the spirit of the invention, as set forth in the appended claims.

Having thus described my invention, what 80 I claim as new and desire to secure by Letters Patent, is:

1. A presser foot for sewing machines including a shank, a foot carried thereby and having a guiding slot for the upturned 85 edges of fabric sections to be trimmed, a strip deflector extending across said slot with its lower edge adjacent the upper surface of the foot, and means for supporting said strip deflector, whereby the same may be 90 moved laterally and upwardly to inoperative position.

2. A presser foot for sewing machines including a shank, a foot carried thereby and having a guiding slot for the upturned edges 95 of fabric sections to be trimmed, a strip deflector extending across said slot with its lower edge adjacent the upper surface of the foot, and means for pivotally supporting said strip deflector, whereby the same may 100 be moved laterally and upwardly to inoperative position.

3. A presser foot for sewing machines including a shank, a foot carried thereby and having a guiding slot for the upturned edges 105 of fabric sections to be trimmed, said presser foot having a clamping member for holding a stationary trimming blade, a strip deflector extending across said slot with its lower edge adjacent the upper surface of the foot, and means for supporting said strip deflector, whereby the same may be moved laterally and upwardly to clear said clamping member when the strip deflector is turned to 110 inoperative position.

4. A presser foot for sewing machines including a shank, a foot carried thereby and having a guiding slot for the upturned edges 115 of fabric sections to be trimmed, a strip deflector extending across said slot with its lower edge adjacent the upper surface of the foot, a pivoted support for said strip deflector, said pivotal support being inclined to the vertical and so disposed that said strip deflector will swing in a plane inclined to a 120 vertical plane extending longitudinally of the presser foot when said strip deflector is being moved to inoperative position.

5. A presser foot for sewing machines including a shank, a foot carried thereby hav- 125

- ing a guiding slot for the upturned edges of the fabric sections to be trimmed, a removable plate carried by said presser foot and having a needle opening therein, and a 5 stitch tongue carried by said removable plate and extending into said needle opening, said stitch tongue being disposed in the plane of said removable plate.
6. A presser foot for sewing machines including a shank, a foot carried thereby having a guiding slot for the upturned edges of the fabric sections to be trimmed, a removable plate detachably secured to the under face of said presser foot and having 10 15 needle openings therein, one in rear of the other, and stitch tongues extending respectively into the needle openings, said guiding slot being located in advance of said plate and in line with said needle openings.
- 20 7. A presser foot for sewing machines including a shank, a foot carried thereby having a guiding slot for the upturned edges of the fabric sections to be trimmed, a removable plate detachably secured to the under 25 30 face of said presser foot and having needle openings therein, one in rear of the other, stitch tongues extending respectively into the needle openings, said guiding slot being located in advance of said plate and in line with said needle openings, a strip deflector normally extending across said guiding slot, and means for supporting said strip deflector, whereby the same may be moved laterally and upwardly to inoperative position.
8. A presser foot for sewing machines including a shank, a foot carried thereby and having a guiding slot for the upturned edges of fabric sections to be trimmed, a strip deflector extending across said slot with its lower edge adjacent the upper surface of the 35 40 45 foot, means for supporting said strip deflector, whereby the same may be moved laterally and upwardly to inoperative position, and adjustable means for maintaining said strip deflector in either of its extreme positions.
9. A presser foot for sewing machines including a shank, a foot carried thereby and having a guiding slot for the upturned edges of fabric sections to be trimmed, said presser 50 55 60 foot having a clamping member for holding a stationary trimming blade, a strip deflector extending across said slot with its lower edge adjacent the upper surface of the foot, means for supporting said strip deflector, whereby the same may be moved laterally and upwardly to clear said clamping member when the strip deflector is turned to inoperative position, and adjustable means for maintaining said strip deflector in either of its extreme positions.

In testimony whereof, I affix my signature, in the presence of two witnesses.
